Primary Examiner — Susan E Krakower*Assistant Examiner* — Jerry Shiuan-Hua Hsu(57) **CLAIM**

The ornamental design for a cover for car console as shown and described.

DESCRIPTION

FIG. 1 is a front, right, and bottom perspective view of a cover for car console, showing my new design;

FIG. 2 is a rear, left, and top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged detail view showing area 9 in FIG. 2.

The short-dash and long-dash broken lines in FIGS. 2 and 9 denote the boundaries and lead lines for the enlarged detail areas and form no part of the claimed design.
